GEM SETTING OR SIMILAR ARTICLE

Joseph Weiss, Maplewood, N. J., assignor to
 Tessler & Weiss, Inc., Newark, N. J., a corpora-
 tion of New Jersey

Application January 12, 1950, Serial No. 7,180

Term of patent 7 years

(Cl. D45—1)

To all whom it may concern:

Be it known that I, Joseph Weiss, a citizen of the United States, and a resident of Maplewood, New Jersey, have invented a new, original, and ornamental Design for a Gem Setting or Similar Article, of which the following is a specification, reference being had to the accompanying drawing, forming a part thereof, in which

Figure 1 is a top plan view of a gem setting or similar article, showing my new design;

Figure 2 is a side elevational view thereof;

Figure 3 is an end elevational view thereof;

Figure 4 is a bottom plan view thereof; and

Figure 5 is a section on the line 5—5 of Figure 1.

I claim:

The ornamental design for a gem setting or similar article, as shown.

JOSEPH WEISS.
